UNITED STATES PATENT OFFICE.

THOMAS G. AMSDEN, OF BUFFALO, NEW YORK, ASSIGNOR TO JOHN W. TOTTERDALE,
OF STAFFORD, NEW YORK.

CLOTHES-DRYING RACK.

1,027,303.

Specification of Letters Patent.

Patented May 21, 1912.

Application filed March 30, 1910. Serial No. 552,353.

To all whom it may concern.

Be it known that I, THOMAS G. AMSDEN, a citizen of the United States, and resident of Buffalo, in the county of Erie and State of New York, have invented certain new and useful Improvements in Clothes-Drying Racks, of which the following is a specification.

My invention relates to improvements in clothes drying racks and it has for its primary object the provision of a rack of this character by means of which the portions of the clothes in contact with the supporting bars are as quickly dried as the parts thereof hanging from the bars.

Another object of my invention is the provision of means for quickly and securely fastening the rack to a stove-pipe so that it may be positioned over the stove and the clothes supported thereon be thereby subjected to the heat rising from the stove, thus more quickly drying the clothes hung upon the rack.

A further object of my invention is the provision of hollow open-ended supporting-arms whereby the heat is permitted to enter said arms and thus dry the portions of the clothes in contact with the bar as quickly as the depending portions thereof.

With these and other objects in view, my invention consists in the construction, arrangement, and combination of parts and in the particular construction of the supporting-arms, as will be hereinafter described and particularly pointed out in the subjoined claim.

In the drawings,—Figure 1 is a perspective view of my improved drying rack fastened to a stove-pipe. Fig. 2 is a horizontal section taken on line 2—2, Fig. 1. Fig. 3 is a vertical section taken on line 3—3, Fig. 2. Fig. 4 is a longitudinal section of a portion of one of the supporting arms. Fig. 5 is a cross-section of one of the supporting arms. Fig. 6 is a detached perspective view of the securing band by means of which the rack-proper is secured to the stove-pipe.

Referring now to the drawings in detail, like letters of reference refer to like parts in the several figures.

The reference letter A designates a stove-pipe to which my improved clothes drying-rack B is attached by means of the securing-band C.

The securing-band comprises a segmental 55 plate c having an elongated vertically-disposed opening c¹ near each end and passing through said openings are segmental band-members D having one of their ends passed through the openings c¹ and recurved, as at 60 d, so as to provide a secure fastening to the plate c. The opposite ends of said segmental band-members have outstanding ears d¹ provided with alined perforations through which a clamping screw E is passed; said 65 screw being of any practicable construction capable of drawing the outer ends of the band-members together when the securing band is placed around a stove-pipe.

The segmental plate c is made of thin 70 sheet metal so that its shape or curvature can be readily altered to conform to the diameter of the stove-pipe around which the securing band is to be placed and the band-members D are also flexible and provided 75 with a series of openings at corresponding points so that when the securing band is to be placed around a stove-pipe, said members can be bent at the desired points to bring the corresponding openings into registration 80 so as to receive the clamping-screw by means of which the band is securely fastened to the stove-pipe. By making the clamping screw of considerable length, the outer ends of the band-members need not be brought 85 in contact, as the screw will easily extend through the separated outstanding lugs. When it is desired to retain the securing-band on the stove-pipe, the outstanding lugs may be cut off adjacent the point where the 90 clamping-screw passes through, provided it was found necessary to use the second set of openings in the band-members in order to secure the band to the stove-pipe. As the band-members are made of thin material, 95 I preferably provide the clamping screw with a collar e near one end and apply a nut e¹ to its opposite end, which nut may be threaded onto the screw to the extent needed to securely fasten the band to the stove-pipe. The opposite recurved ends d of the band-members lie in contact with the stove-pipe and are therefore prevented from becoming detached from the plate c.

Arranged vertically between the ends of 105 the segmental plate c is a fastening-bar F having a narrow upturned hook f at its lower end and a narrow off-set extension f¹

at its upper end; said hook and extension being preferably in alinement for a purpose to appear hereinafter.

My improved drying-rack proper is of that general form in which the supporting-arms can be swung laterally and separated to the extent desired; said arms being pivotally secured to a head capable of swinging vertically on a hanger; and in the drawings,

10 G designates the hanger which is formed of a flat piece of metal having an opening g at its upper end and a notch g^1 at its lower end; and pivotally affixed to said hanger so as to swing vertically thereon, is a head H comprising two substantially flat plates h , h^1 between which the inner ends of the supporting-arms I are pivotally secured so that they may swing laterally through an arc of a circle.

20 As the connection of the head H to the hanger G forms no part of my invention and is now in common use, I deem it unnecessary to describe or illustrate the same in detail.

25 J designates a retainer-arm formed of wire secured at its upper end to the hanger G, as at j , so that it may swing on said hanger, and at its lower end it has a hook j^1 adapted to engage the plate h of the supporting head H as clearly shown in Fig. 3.

In order to secure the drying-rack to the band C, it is simply necessary to position the hanger G so that the extension f^1 of the bar F can be passed through the opening g of the hanger and so that the bight of the upturned hook f of said hanger will enter the notch g^1 at the lower end of said hanger. This will properly support the rack over the stove so that the clothing suspended 35 from the supporting-arms will be thoroughly and quickly dried. When not in use, the supporting-arms with the head H may be swung to hang vertically, it being simply necessary to disengage the hook j^1 of the 40 retainer-arm from the plate h of said head, whereupon the latter and the arms I will gravitate and assume such position, thus occupying but little space.

One of the essential features of my invention resides in the supporting-arms I which are made hollow, as shown in Figs. 4 and 5 and tapered from their inner ends toward their outer ends. Each of these arms is in the form of tubes constructed of a strip of metal bent or curved so that the longitudinal edges abut, as shown in Fig. 5, and the ends of these arms are open so that the air can pass through them and thus dry the portions of the clothing in contact with the arms as quickly and as thoroughly as the 55 portions suspended therefrom, particularly so when the rack is supported over a stove in the path of the ascending hot air.

Having thus described my invention, what I claim is,—

In a clothes drying-rack, the combination with a stove-pipe, of a securing-band encircling said stove-pipe and comprising a segmental plate having an opening near each end, two oppositely-curved band-members 70 having one of their ends passed through said openings and recurved to lie against the inner face of said segmental plate and their opposite ends provided with outstanding lugs, a clamping-screw passed through said lugs, a vertically-disposed bar fastened to the outer face of said segmental plate and having an upstanding extension at its upper end and an upwardly-directed hook at its lower end, a vertically-disposed hanger 80 having an opening near its upper end through which said narrow extension is passed and a notch at its lower end into which the bight of said upwardly-directed hook enters, a plurality of clothes supporting-arms arranged to swing on said hanger, and means to retain said arms in either vertical or horizontal position.

In testimony whereof, I have affixed my signature in the presence of two subscribing 85 witnesses.

THOMAS G. AMSDEN.
